UNITED STATES PATENT OFFICE.

EDWARD E. GOLD, OF NEW YORK, N. Y.

DESIGN FOR AN ELECTRIC-HEATER CASING.

SPECIFICATION forming part of Design No. 29,976, dated January 10, 1899.

Application filed September 17, 1898. Serial No. 691,249. Term of patent 14 years.

To all whom it may concern:

Be it known that I, EDWARD E. GOLD, a citizen of the United States, residing in the city, county, and State of New York, have invented a certain new and original Design for Electric-Heater Casings, of which the following is a specification.

My new design for the casing of an electric heater is shown in the accompanying drawings, wherein—

Figure 1 is a side elevation, and Fig. 2 an end elevation.

My casing has a foraminous tubular body portion A, end heads B B, and cap-plates C C. The tubular body A is cylindrical and is made ornamenteally foraminous by elongated openings or slots a a, which extend in circumferential direction and are arranged close together side by side in longitudinal rows, as

clearly shown in Fig. 1. The opposite end portions A' A' of the tubular body are devoid of perforations. The heads B B are of somewhat larger diameter than the body A and their visible portions have the form of thick circular disks, as shown, with beveled or rounded portions b b. The end plates C C are flat circular disks.

I claim—

The design for an electric-heater casing herein shown and described.

In witness whereof I have hereunto signed my name in the presence of two subscribing witnesses.

EDWARD E. GOLD.

Witnesses:

GEORGE H. FRASER,
THOMAS F. WALLACE.
